DISH AND UTENSIL BASKET FOR DISHWASHING MACHINES

George L. Hilleman, St. Louis County, Mo., assignor to Vulcan Manufacturing Company, Inc., St. Louis, Mo., a corporation of Missouri

Filed Jan. 3, 1967, Ser. No. 5,289

Term of patent 3½ years

(Cl. D49—1)

FIG. 1

I claim:

The ornamental design for a dish and utensil basket for dishwashing machines, as shown.
